UNITED STATES PATENT OFFICE.

HERMENEGILDE J. H. LAFLECHE, OF CASSELMAN, ONTARIO, CANADA.

MAIL-TRANSFERRING APPARATUS.

1,235,578.

Specification of Letters Patent.

Patented Aug. 7, 1917.

Application filed September 22, 1916. Serial No. 121,662.

To all whom it may concern:

Be it known that I, HERMENEGILDE J. H. LAFLECHE, a subject of the King of Great Britain, residing at Casselman, in the Province of Ontario, and Dominion of Canada, have invented certain new and useful Improvements in Mail-Transferring Apparatus, of which the following is a specification.

This invention relates to a transferring apparatus designed to be used in connection with railway mail service for automatically and simultaneously interchanging mail sacks between a moving train and the station and between two moving trains without danger 15 of injuring the sacks or their contents.

This invention is designed to provide a sack carrier to be used in connection with a collecting and delivering head both on the train and on the station apparatus, which 20 carrier when supported from one head will be in proper position for collection by the other head, whether the latter be on a moving train or at the station.

With this as the principal object in view 25 the invention consists of the novel construction, combination and arrangement of parts set forth in the following specification, pointed out in the appended claim and illustrated in the accompanying drawings, in 30 which—

Figure 1 is a side elevation of a mail sack transferring apparatus showing the positions of the sack carriers on the train and station supports just previous to transfer- 35 ring the sacks,

Fig. 2 is an end view of the station apparatus and sack carrier as seen from the right of Fig. 1,

Fig. 3 is a similar view of the apparatus 40 and carrier used on the car and viewed from the same point.

In the drawings 10 indicates a portion of a mail car through the door 11 of which a swinging horizontal arm 12 is adapted to 45 be projected. This arm as shown has a vertical stem 14 on its inner end that turns freely in two loops or eyes 15 secured one above the other to the door frame of the car and within the car. A shoulder 16 on 50 the stem 14 just below the arm 12 rests upon the upper loop or eye 15 when the arm is in its lowermost position and forms the bearing upon which said arm may be swung into or out of the car.

55 Fixed against the outer face of the door frame is a hook 17 that projects inwardly

beyond the side of the door and which engages the arm 12 holding it in its extended position against the door frame perpendicular to the side of the car. Above the 60 hook 17 is a second hook 19 to support the arm at a higher elevation which is necessary under certain conditions to be herein-after set forth, the stem 14 sliding freely in the eyes 15 when the arm is raised and 65 lowered.

Centrally pivoted to the outer end of the arm 12 and above said arm is a mail bag delivering and receiving head 20, from the opposite ends of which project fingers 21 and 23, respectively. A similar collecting 70 and delivering head 20^a is pivoted upon the outer end of an arm 33 rigidly mounted upon a vertical post 34 and projecting horizontally from said post.

75 For the purpose of suspending one or more mail sacks from one of said heads in order that it may be collected by the other as the train passes a station, there is provided a rod 36 forked at its lower end as at 37 the 80 ends of the latter terminating in eyes connected by a loosely hanging chain 38. One end of the chain is fixed to one of said eyes and the other end provided with the snap hook 39 removably connected to the other 85 eye. This chain is passed through a strap handle provided on all mail sacks and a snap hook connected to the eye on fork 37 so that the mail sack A will be suspended 90 from the chain. If desired two or more sacks may be hung from the chain as is evident. Just above the fork 37 the rod 36 is provided with a flattened portion 40 from opposite sides of which project studs 41 and 42, the studs 41 being in line with each other 95 as are the studs 42. The studs 41 and 42 on each side are diagonally disposed with relation to each other, being spaced vertically a distance equal to the thickness or diameter of the arms 21 and 23 and horizontally spaced sufficiently far to offset them from the vertical center of the rod 36. The upper end of the rod terminates in a ball 43.

100 In using this apparatus to transfer mail sacks between a moving train and a station, the arm 12 being within the car is, upon approaching a station, swung outwardly and raised slightly in order to engage it with the hook 17 that holds the arm in extended position. Before swinging the arm outwardly a sack carrying rod 36 with a mail sack attached thereto is mounted on the head 105

20 by pushing the flattened portion 40 of the rod 36 between the fingers 21 so that the studs 41 will lie above the fingers and support the rod and sack, while the studs 42 5 extend outwardly below said fingers. In placing the rod between the fingers 21, care must be taken that the studs 41 will be in advance of or toward the direction of movement of the train, see Fig. 1, so that normally 10 the weight of the bag tends to swing the upper end of arm 36 rearwardly, the studs 41 acting as a pivot, but owing to the pressure of the air against the sack caused by the moving train, the rod 36 is held in vertical position and prevented from rocking 15 or tilting in the opposite direction by the studs 42 which bear upon the under side of the fingers 21.

A similar rod 36 having one or more mail 20 sacks attached thereto is suspended from the fingers 21 of the head 20^a at a station, the fixed position of the arm 33 supporting the head 20^a being such as to maintain said head at a higher elevation than the head 20 on the 25 car 10. The rod 36, however, is sufficiently long between the ball 43 and the studs 41 to cause the studs to hang below the fingers 23 of the opposite head when the rod is operatively suspended by the ball, and thus enable 30 said rod with the sacks attached to be collected, notwithstanding any vertical rocking of the car, and sustained after collection by the ball. It will not be necessary to provide against swinging of the bag and rod

at the station because the support at such point being fixed the strength of the normal wing against the bag will rarely be sufficient to cause any noticeable movement of the rod. The collecting fingers of both heads, it will be seen, will support the rods by the balls 40 after the transferring operation has taken place.

As the head 20 approaches the head 20^a, the ends of the fingers 23 of each head pass on opposite sides of the rod 36 supported by the opposite head and remove the mail sack carriers from their supporting heads. The arm 12 will then be swung into the car and the sacks removed.

What I claim is:

In a mail transferring apparatus, means for holding mail sacks comprising a rod having a forked lower end with an eye at the terminal of each branch, a spherical upper end, and a flattened section therebetween, a pair of supporting studs projecting in alignment from each side of said flattened portion in different vertical and horizontal planes, and a flexible connection between the branches of the forked lower end of the rod from which to hang mail sacks.

In testimony whereof I affix my signature in presence of two witnesses.

HERMENEGILDE J. H. LAFLECHE.
